UNITED STATES PATENT OFFICE.

HENRY B. COSTANTIN, OF BROOKLYN, NEW YORK, ASSIGNOR TO C. KENYON COMPANY, INC., OF BROOKLYN, NEW YORK, A CORPORATION OF NEW YORK.

DESIGN FOR A TIRE TREAD.

Application filed August 2, 1924. Serial No. 10,342. Term of patent 14 years.

To all whom it may concern:

Be it known that I, HENRY B. COSTANTIN, a citizen of the United States of America, residing at Brooklyn, in the county of Kings, city and State of New York, have invented a new, original, and ornamental Design for a Tire Tread, of which the following is a specification, reference being had to the accompanying drawing, forming a part thereof.

In the drawing—

Figure 1 is a detail plan view showing the tire tread, and

Figure 2 is a perspective view showing a section of the tire with the tread therein.

I claim:

The design for a tire tread substantially as shown.

HENRY B. COSTANTIN.
